UNITED STATES PATENT OFFICE.

CHARLES H. RICHARDS, OF AURORA, ILLINOIS, ASSIGNOR TO RICHSO MANUFACTURING CO., OF AURORA, ILLINOIS, A CORPORATION OF ILLINOIS.

CASING OR TRIM FOR PLASTERED WALLS.

Application filed June 27, 1927. Serial No. 201,741.

This invention relates to a new and improved casing or trim for plastered walls, and more especially to such a casing or trim adapted to serve to cover and protect the 5 marginal edge of plastered walls around openings such as door and window openings, and the like.

One of the features of my invention is to provide such a casing or trim which also 10 serves as a finishing edge and protection for plastered walls, such casing or trim forming a ground, or gage to determine the thickness of the plaster coating on the wall.

My improved casing or trim is strong and 15 rugged, and cheap to manufacture. It is also easily applied and presents a neat and finished appearance.

Other features and advantages of my invention will appear more fully as I proceed with my specification.

In that form of device embodying the features of my invention shown in the accompanying drawings, Figure 1 is a sectional and elevational view of the edge of a 25 wall adjacent an opening, for example a door opening, Fig. 2 is a view taken as indicated by the line 2 of Fig. 1, and Fig. 3 is a view in perspective of a strip of my improved casing or trim showing the same removed from the wall.

As shown in the drawings, 10 indicates the inside of a wall or partition terminating in a stud 11, here shown as a wooden 2 x 4, and usually referred to as a buck.

15 indicates the plaster on the wall.

16 indicates, in general, a piece of casing or trim preferably formed out of a strip of sheet metal. This strip has a flat end portion indicated by 16^a the edge of which is 40 adapted to be nailed to the end face of the buck 11 by means of the nails 17 through the holes 17^a. The outer edge of the portion 16^a has a narrow margin 16^b bent substantially 45 at right angles thereto and the material from the edge of this margin 16^b is bent inwardly toward the portion 16^a as indicated by 16^c thence again outwardly and 50 away therefrom as indicated by 16^d, the extreme marginal edge as indicated by 16^e lying at right angles to the portion 16^a and adapted for attachment to the side face of 55 the buck 11 by means of the nails 18 through the holes 18^a.

The portion 16^d of the strip is preferably provided with holes 19 through which the plaster may be caused to pass to key the same to the trim. This keying or locking of the plaster is also assisted by the portion 60 16^e of the casing or trim which overlies the edge of the plaster and assists in holding the same in place.

The frame member 12 is usually spaced some distance from the end face of the buck 65 11 thus leaving a crack 20. I prefer to cover this crack by means of the moulding 21 nailed to the edge of the frame 12 by means of the nails 22.

While I have shown and described certain embodiments of my invention, it is to be understood that it is capable of many modifications. Changes, therefore, in the construction and arrangement may be made without departing from the spirit and scope 70 of the invention disclosed in the appended claims, in which it is my intention to claim all novelty in my invention as broadly as possible in view of the prior art.

What I claim is new, and desire to secure 80 by Letters Patent, is:

1. A sheet metal casing or trim for a wall opening comprising a strip of metal having an end portion adapted for attachment to the end face of a wall, the outer edge of 85 said end portion having a margin bent substantially at right angles thereto, the material at the edge of said margin being bent backwardly toward the end portion and thence away therefrom, the extreme marginal edge thereof lying at right angles to the end portion and adapted for attachment to the side face of a wall.

2. A sheet metal casing or trim for a wall opening comprising a strip of metal having an end portion adapted for attachment to the end face of a wall, the outer edge of said 95 end portion having a margin bent substantially at right angles thereto, the material at the edge of said margin being bent backwardly toward the end portion and thence away therefrom and provided with plaster locking apertures, the extreme marginal edge thereof adapted for attachment to the side face of a wall.

In witness whereof, I have hereunto set my hand this 23rd day of June, 1927.

CHARLES H. RICHARDS.
